UNITED STATES PATENT OFFICE.

MILTON H. SHOENBERG, OF SAN FRANCISCO, CALIFORNIA, ASSIGNOR OF
ONE-HALF TO BERNARD LOWENSTEIN, OF SAN FRANCISCO, CALIFORNIA.

ELECTRICAL HEATER.

No. 852,853.

Specification of Letters Patent.

Patented May 7, 1907.

Application filed September 13, 1906. Serial No. 334,408.

To all whom it may concern:

Be it known that I, MILTON H. SHOENBERG, a citizen of the United States, residing in the city and county of San Francisco and State of California, have invented new and useful Improvements in Electrical Heaters, of which the following is a specification.

My invention relates to an electrical heating apparatus.

It consists in the combination of heating elements with connecting terminals, and their relation to the body to be heated.

It also comprises details of construction which will be more fully explained by reference to the accompanying drawings, in which—

Figure 1 illustrates an element. Figs. 2 & 3 its application to a laundry iron.

It is the object of this invention to provide an improved electrical heater. I have in the present illustration shown such a heater in conjunction with a laundry iron.

A represents the hollow base of such an iron, and B is a top or cover which may be secured upon the base by screws or in other convenient manner, and by means of a handle C attached to the cover the iron may be properly manipulated. In order to heat this iron I employ a core which is made up of a plurality of plates 2 and 3. These plates are of such form as to fit the cavity in the base A and are separated from each other by an insulating material, preferably thin sheets of mica; similar insulating material is also fitted around the exterior of the plates, and naked electrical conducting wires 6 are wound tightly around the outside of the plates and insulation, thus binding the whole closely and firmly together, these wires being sufficiently separated from each other to prevent short-circuiting.

One end of the wire connects with one end of one of the plates, and the opposite end is connected with the opposite end of the other plate; these plates forming the core upon which the coil is made.

Each of the plates has a projecting pole or connection as at 4—5; these may be turned upward or otherwise conveniently disposed so that connection therewith may be made at one end of the apparatus where both these poles are located. This avoids the necessity of a return wire to the rear end of the iron or other body to be heated.

The core plates with their terminals are 55 preferably stamped or formed in a single piece, and the element is thus easily placed in the body to be heated or removed therefrom in case repairs or inspection should be necessary.

The structure thus formed is compressed into the container and heat will be transmitted from the structure to the container or body to be heated; the proportionate bulk of which serves to absorb the heat, and by reason of the compression, the heat is easily transmitted. The bulk of the exterior body to be heated serves to absorb any surplus heat, and thus prevent over-heating of the wires and consequent burning out of the parts.

In Figs. 2 and 3 I have particularly shown means for regulating the heat where a plurality of plates 2—3—3^a are employed.

I have here shown three plates 2, 3, 3^a, and 7^a three poles or plug connections 4, 4^a, 5. If it is desired to dispose the connections so as to provide for different degrees of heat, one end of the wire 6 is connected with the post 4. From the opposite end of the plate 2, the wire is coiled about the plates as previously described, until it reaches the intermediate connection 4^a where the electrical current leaves the apparatus by means of a suitable plug or connection as at 7, and 85 thence through the plate 3 to 4^a. By interrupting this circuit and continuing the current through the wire to the end, and connecting with the pole 5, the whole length of the wire will be included in the circuit and the 90 resistance thus increased.

It will be manifest that by the introduction of a number of such connections the heat imparted may be varied and regulated.

Having thus described my invention, what I claim and desire to secure by Letters Patent is—

1. The combination with a body to be heated of electrical heating elements, said elements comprising a plurality of insulated 100 core plates having integral terminals, insulating means by which said plates are separated, other insulation inclosing the cores and electrically resistant wires wound around said cores and connecting with the terminals.

2. In an electric heater, a mechanism consisting of a plurality of core plates insulated from each other, said cores having terminals

formed integral with them at one end, insulating material inclosing said cores, an electrically resistant naked wire wound around the exterior of said cores and insulation, with the coils separated from each other and connection between said wire and the terminals and core plates.

3. In an electrical heating apparatus, a plurality of flat core plates insulated from each other and having an inclosing insulating film, an electrically resistant naked wire coiled about the cores and their insulation so as to compress the parts together, the coils of said wire being separated from each other, terminals formed integral with the cores and at one end of the structure, the body to be heated having a cavity within which the

heating mechanism is compressed and the parts maintained in close contact.

4. In an electric heater, a plurality of core plates insulated from each other and having independent integral terminals, a single winding of naked wire in separated coils insulated from the core plates and independent connections between said wires and said plates whereby different lengths of wire and resistance may be introduced into the circuit.

In testimony whereof I have hereunto set my hand in presence of two subscribing witnesses.

MILTON H. SHOENBERG.
